CUE AND BALL RACK

Jack D. Allen, Genoa Township, Delaware County, Ohio
(5253 Nautilus Drive, Cape Coral, Fla. 33904)

Filed May 29, 1967, Ser. No. 7,297

Term of patent 14 years

(Cl. D33—3)

FIG. 1.

FIG. 2.

FIGURE 1 is a front perspective view of a cue and ball rack embodying the design of my invention, it being understood that the reverse side of the cue and ball rack shown has the general appearance of a body formed with a profile configuration substantially reversed from that shown in FIG. 1.

FIGURE 2 is an enlarged, fragmentary view in longitudinal section, taken along the line 2-2 of FIG. 1.

The six elements shown in horizontal array upon the recessed plane surface, located parallel to the upper margin of FIG. 1, represent cue-retaining clip devices.

I claim:

The ornamental design for a cue and ball rack, substantially as shown and described.
